BEDCOVER-SUPPORTING MEANS

Lewis L. Hinton, Houston, Tex.

Application March 12, 1948, Serial No. 14,452

5 Claims. (Cl. 5—319)

1
My invention relates to means for supporting the bed covers of a bed vertically of the upper surface of the mattress, whereby to prevent the weight of the covers from being imposed upon the feet of a person occupying the bed. As is well known, the weight of the bed covers on the feet of a sleeper, especially when sleeping on the back, frequently causes cramps in the feet. Likewise, in the case of injured feet, it is essential that the same be protected from the weight of covers to avoid discomfort to the occupant of the bed.

With the foregoing in view, an object of my invention is to provide an improved bed cover-supporting means for a bed.

A further object is to provide an improved bed cover-supporting means which includes novel means for attaching the same to a mattress, and/or novel means for adjusting the angular relationship of the cover-supporting frame to the mattress, and/or novel means for locking the attaching means in a mattress-clamping relation.

A further object of the invention is to provide an improved bed cover-supporting means which includes a novel pad for the frame of the cover support, a novel cover for the pad, and novel means for detachably connecting the pad and cover to the frame.

A further object is to provide in a bed cover-supporting means, novel means for supporting the bed covers in vertically-disposed relation to one end of a bed.

Other objects and advantages reside in the particular structure of the invention, combination and arrangement of the several parts thereof, and will be readily apparent to those skilled in the art upon reference to the attached drawings in connection with the following specification, wherein the invention is shown, described and claimed.

In the drawings:

Figure 1 is a fragmentary end elevation of a bed showing a bed cover support according to the invention attached thereto;

Figure 2 is a plan view thereof, parts of the bed being shown in horizontal section;

Figure 3 is a fragmentary transverse vertical section taken substantially on the plane of the line 3—3 of Figure 2;

Figure 4 is a fragmentary elevation of the supporting frame for the bed covers apart from the rest of the structure.

In the drawings, wherein like reference characters have been used throughout the several views to designate like parts, 10 designates the

2
footboard for a bed and 11 the mattress thereof. Any suitable bed and/or mattress may be utilized, as will appear hereinafter. The support according to the invention is adapted to be clamped to the mattress 11 at the foot end thereof by a pair of laterally-spaced clamps 12, each of which is disposed adjacent the side edges of the mattress. As the clamps 12 are identical, it will suffice to describe but a single one of them, and each clamp comprises a pair of upper and lower opposed clamp members. The upper clamp member comprises a leg 13 adapted to rest upon the upper surface of the mattress 11 and includes a foot 14 extending downwardly over the end edge of the mattress. The lower clamp member comprises a leg 15 underlying the lower surface of the mattress and an upwardly-directed foot 16 extending over the end edge of the mattress and pivotally connected to the foot 14 in toe-to-toe relation by a horizontally-disposed pivot means 17. By virtue of this connection, the clamp members are swingable to and from clamping and unclamping positions with relation to the mattress 11.

25
The lower foot 16 includes a rigid upwardly-directed extension 18 which extends behind the foot 14 of the upper clamp member, whereby to limit relative unclamping movement of the clamp members. The leg 13 of each upper clamp member includes a vertically-disposed quadrant 19. The quadrant 19 has the periphery thereof formed to provide series of major latch teeth 20 and minor latch teeth 21. The upper end of the extension 18 of the lower foot 16 has pivotally secured thereto in any suitable manner a latch dog 22, the free end of which is selectively engageable with the minor latch teeth 21, whereby to lock the upper and lower legs 13 and 15 in clamping engagement with the mattress 11. Each quadrant 19 is formed to provide an axially-disposed aperture therethrough in which is journaled the stub shaft 23, Figure 4, of a cover-supporting frame 24. The frame 24 includes end frame members 25 which mount vertically-spaced ears 26, which in turn are provided with aligned apertures slidably receiving the latch dog 27. The latch dog 27 is vertically movable in the ears 26 and is provided with a laterally-directed lower free end portion 28 which is selectively seatable between adjacent major teeth 20 to lock the frame in angularly adjusted relation to the upper clamp members 13 and/or to the mattress 11. The frame 24 likewise includes a plurality of upwardly-directed frame-providing members 29 and the frame as a whole is preferably covered with a grid of wire screening or the like 30.

The upper ends of the frame-providing members 25 and 29 are longitudinally directed toward the head of the bed, as at 31, Figure 3, whereby to provide a canopy. The forward edges of the forwardly-directed ends of the frame-providing members 25 and 29 are preferably connected by any suitable frame members, not shown, which are in turn covered with a layer or sheath of sponge rubber, or the like, 32. Such sheath of sponge rubber obviously protects the toes of the 10 occupant of the bed from injury.

To exclude drafts from the bed, I prefer to utilize a pad 33 of sponge rubber, over the forward surface of the frame, Figure 3, which pad is coextensive with the frame, whereby to substantially exclude all air from passage through the grid 30. The pad 33 is covered with a slip cover 34 provided at its upper edge abutting the grid 30 with suitable tie strings 35, whereby the cover and pad may be suitably secured to the frame. The cover 34 is provided with an extension flap 36 which overlies not only the canopy of the upper edge of the frame, but also extends downwardly to completely enclose the frame. The lower free edge 37 of the extension of the 15 slip cover terminates in the region of the lower edge of the frame and is secured thereto by suitable means, such as the tie strings 39. Thus, the slip cover 34, together with its extension, not only provides a sanitary cover for the frame and the pad therefor, but also may be, and preferably is, made in fabric of distinctive appearance, whereby the cover presents an attractive appearance or in use, or when not in use, but disposed on or adjacent the bed.

As is readily apparent from Figure 3, the bedcover-supporting means according to the invention permits any suitable bedcovers, diagrammatically illustrated at 40 in Figure 3, to be utilized with the device in the normal manner. The sole exception is that the lower ends of the covers 40 are extended over the frame of the device and are thereafter tucked into the space below the mattress in the usual manner. At the same time, the dual series of major and minor teeth on the quadrants 19 provide a relatively simple means for accommodating the device to mattresses of varying thicknesses and also to permit the support of the frame in various angular relations to the mattress.

Thus, while I have shown and described what is now thought to be the preferred embodiment of the invention, it is to be understood that the same is susceptible of other forms and expressions. Consequently, I do not limit myself to the precise structure shown and described hereinabove, except as hereinafter claimed.

I claim:

1. In a bedcover-supporting means, including a bedcover-supporting frame, the improvement comprising a pair of laterally-spaced clamps each adapted to clamp a mattress therebetween adjacent the side edges thereof, each clamp being U-shaped and comprising a pair of L-shaped upper and lower clamp members, each comprising a leg and a foot, horizontally-disposed pivot means pivotally connecting said feet together in toe-to-toe relation, a rigid extension of the lower foot extending upwardly behind the upper foot to limit pivotal movement of said members in an unclamping direction, a quadrant carried by the leg of said upper member and extending upwardly thereof, said quadrant including peripheral series of major and minor latch teeth, a 15 latch dog carried by said extension and engage-

able with said minor latch teeth to lock said clamp members in clamping relation to a mattress, means pivotally connecting said frame to each quadrant, and latches carried by said frame and engageable with said major latch teeth to lock said frame in a selected angularly-disposed relation to said mattress.

2. In a bedcover-supporting means, including a bedcover-supporting frame, the improvement comprising a pair of laterally-spaced clamps each adapted to clamp a mattress therebetween adjacent the side edges thereof, each clamp being U-shaped and comprising a pair of L-shaped upper and lower clamp members, each comprising a leg and a foot, horizontally-disposed pivot means pivotally connecting said feet together in toe-to-toe relation, a rigid extension of the lower foot extending upwardly behind the upper foot to limit pivotal movement of said members in an unclamping direction, a quadrant carried by the leg of said upper member and extending upwardly thereof, said quadrant including peripheral series of major and minor latch teeth, a latch dog carried by said extension and engageable with said minor latch teeth to lock said clamp members in clamping relation to a mattress, means pivotally connecting said frame to each quadrant, latches carried by said frame and engageable with said major latch teeth to lock said frame in a selected angularly-disposed relation to said mattress, a pad for said frame, a combined cover for said pad and frame, and means detachably securing said pad and cover to said frame.

3. In a bedcover-supporting means, including a bedcover-supporting frame, the improvement comprising a pair of laterally-spaced clamps each adapted to clamp a mattress therebetween adjacent the side edges thereof, each clamp including opposed upper and lower clamp members, means pivotally connecting said members for clamping and unclamping movement, a limit stop carried by said lower member and engageable with a portion of the upper clamp member to limit unclamping movement thereof, a quadrant carried by said upper clamp member and extending upwardly thereof, said quadrant including peripheral series of major and minor latch teeth, a latch dog carried by said limit stop and engageable with said minor latch teeth to lock said clamp members in clamping relation to a mattress, means pivotally connecting said frame to each quadrant, and latches carried by said frame and engageable with said major latch teeth to lock said frame in a selected angularly-disposed relation to said mattress.

4. In a bedcover-supporting means, including a bedcover-supporting frame, the improvement comprising a pair of laterally-spaced clamps each adapted to clamp a mattress therebetween adjacent the side edges thereof, each clamp including opposed upper and lower clamp members, means pivotally connecting said members for clamping and unclamping movement, a quadrant carried by said upper clamp member, peripheral teeth on said quadrant, means pivotally connecting said frame to each quadrant, and separate latches carried by said frame and lower clamp member, said latches both being engageable with teeth of said quadrant whereby respectively to lock said frame in angularly-adjusted relation to said upper clamp member and to lock said upper and lower clamp members in clamping relation to a mattress.

5. In a bedcover-supporting means including

a bedcover-supporting frame, the improvement comprising a pair of laterally-spaced clamps each adapted to clamp a mattress therebetween adjacent the side edges thereof, each clamp including opposed upper and lower clamp members, means pivotally connecting said members for clamping and unclamping movement, locking means carried by each of said upper clamp members, means pivotally connecting each locking means to said frame, and respective latch elements carried by said frame and lower clamp members, said latch elements being engageable with portions of the locking means whereby respectively to lock said frame in angularly-adjusted relation to said upper clamp member and 15

to lock said upper and lower clamp members in clamping relation to a mattress.
